UNITED STATES PATENT OFFICE.

WALTER ROYAL LOCKHART, OF DELTA, COLORADO.

FIGURE TOY.

1,294,128.

Specification of Letters Patent. Patented Feb. 11, 1919.

Application filed August 8, 1916. Serial No. 113,842.

To all whom it may concern:

Be it known that I, WALTER ROYAL LOCKHART, a citizen of the United States, residing at Delta, in the State of Colorado, have 5 invented a new and useful Figure Toy, of which the following is a specification.

My invention relates to improvements in figure toys.

The object of my invention is to provide 10 a toy in which three figures are employed. One figure is arranged to knock down one of the other figures and the third figure is operated by the downward movement of the other figure, the return of the first figure 15 causing the other figures to return to their normal position ready for another operation.

Another object of my invention is to provide a simple, cheap and effective structure having certain details of structure and operation of parts hereinafter more fully set forth.

In the accompanying drawings:

Figure 1 is a side elevation of my improved toy showing the several figures in 25 dotted lines in their forward position.

Fig. 2 is a vertical sectional view taken on the line 2—2, Fig. 1.

Fig. 3 is a transverse vertical sectional view taken on the line 3—3 of Fig. 1.

30 Referring now to the drawings: A represents a frame of an elongated form, and U-shaped in cross-section; supported by the standards B at each end as clearly shown in Fig. 1 of the drawings. The rear end of 35 the frame has pivoted therein the two stirrups D and D', swinging downwardly and loosely passing through the legs or feet C' of the figure C, which, as shown, is preferably in the form of a goat. Connected to

40 the forward stirrup D is a spring Q, which has its opposite end connected to the frame; whereby the tendency of the spring is to move or hold the figure C in the position shown in dotted lines in Fig. 1. Pivoted in

45 the frame in front of the figure C at J' is a figure J in the form of a man or human being. The figure J has an extension P below its pivot, to which is connected the chain or cable O which extends forwardly over 50 the pulley N mounted in the frame A and extends upwardly.

The extreme forward end of the frame A at one side of the figure J is provided with a rigid figure K in the form of a man;

which has an intermediately pivoted arm L 55 pivoted at L'. The chain or cable O is connected to the arm L on one side of the pivot and a spring M is connected to the arm on the opposite side of its pivot. This normally holds the arm in the position 60 shown in full lines. The arm L carries a hat which is on the head of the figure K and upon the downward movement of the arm the hat is raised.

Connected to the neck of the goat is a 65 cable I which extends forward and is connected to the figure J; so that the figure J is returned to a vertical position when the goat C is moved rearwardly to its normal position. The goat is drawn backwardly 70 by the cord or cable R passing over the pulley S carried by the frame A. The figure C has an opening C² therethrough, as shown in Fig. 3; in which is arranged the trigger E normally held inwardly by the spring T. 75 The trigger E has connected thereto the bar F which is intermediately pivoted to the cross bar G which is secured to the side of the goat or figure C. The lower end of the bar F enters a notch F' in the frame A and 80 holds the goat in its rearward position against the tension of the spring Q.

The operation of the device is as follows: Base balls or the like are thrown at the goat and enter the opening C² in the side thereof 85 and force the trigger E outwardly on the opposite side from which it enters the opening. The outward movement of the trigger rocks the bar F on the bar G and causes the lower end of the bar F to pass inwardly out 90 of the notch F' in the frame A. The spring I draws the goat or figure C forwardly. This strikes the figure J rocking it upon its pivot J' and by the cable or cord O the arm L of the figure K is drawn downwardly 95 removing the hat of said figure. The figures remain in said position and the cable R is then pulled, drawing the goat rearwardly until the bar F catches in the notch F'. The figure J is drawn upwardly in a vertical position by the cable I and the return of this figure to its vertical position allows the spring to return the arm L of the figure K 100 to a position with the hat on the figure.

Having thus fully described my invention, 105 what I claim as new and desire to secure by Letters Patent is:—

1. A toy comprising a movable figure, a

second figure moved by spring tension against the first figure, a catch for holding the second figure in a position against the spring tension, and a third figure operated by the first figure, whereby the release of the second figure operates the other two figures.

2. A toy comprising a movable figure, a second figure moved by spring tension against the movable figure for moving the same, an intermediately pivoted catch for holding the second figure in a position under the spring tension and operated by an object striking it from a right angle direction, and a third figure connected to the movable figure whereby the release of the second figure operates the other two figures.

3. A toy comprising a movable figure, a second figure moved by spring tension against the movable figure for moving the same, a catch for holding the second figure in a position under the spring tension and operated by an object striking it from a right angle direction, and a third figure having a movable arm operated by the first figure whereby the releasing of the second figure operates the first figure and the arm of the third figure.

4. A toy comprising a pivoted figure, a second figure horizontally movable by a spring and adapted to strike and rock the pivoted figure, an intermediately pivoted catch carried by the horizontally movable figure for holding it in a position away from the pivoted figure and operated by an object striking it from a right angle direction, and a third figure having a movable arm operated by the pivoted figure whereby the releasing of the horizontally movable figure operates the other figure and the arm of the third figure.

5. A toy comprising a pivoted figure, a second figure horizontally movable by a spring, adapted to strike and rock the pivoted figure, an intermediately pivoted catch carried by the horizontally movable figure for holding it in a position away from the pivoted figure against the spring tension, its upper end arranged opposite an opening in the figure operated by an object passing through the opening from a right angle direction, and a third figure having a movable arm operated by a cable from the pivoted figure, whereby the releasing of horizontally movable figure operates the other figure and the arm of the third figure.

6. A toy comprising a frame, a pivoted figure, normally held in a vertical position, a horizontally movable spring held figure adapted to move the pivoted figure into a horizontal position, a transversely movable catch carried by the movable figure and engaging the frame, for holding the movable

figure in a rearward position against the tension of the spring.

7. A toy comprising a movable figure, a second figure moved by spring tension against the first figure, a catch for holding the second figure in a position against the spring tension, and a third figure having a movable member connected to one of the other figures, whereby the release of the second figure operates the first figure and the movable member of the third figure, and a spring for returning the movable member of the stationary figure to normal position.

8. A toy comprising a pivoted figure, a second figure horizontally movable by a spring and adapted to strike and rock the pivoted figure, an intermediately pivoted catch carried by the horizontally movable figure for holding it in a position away from the pivoted figure and operated by an object striking it from a right angle direction, and a third figure having a movable arm connected to one of the movable figures, whereby the releasing of the horizontally movable figure operates the other figure and the arm of the third figure.

9. A toy comprising a pivoted figure, a second figure horizontally movable by a spring, adapted to strike and rock the pivoted figure, an intermediately pivoted catch carried by the horizontally movable figure for holding it in a position away from the pivoted figure against the spring tension, its upper end arranged opposite an opening in the figure and operated by an object passing through the opening from a right angle direction, and a third figure having a movable arm operated by a cable from one of the other figures, whereby the releasing of the horizontally movable figure operates the other figure and the arm of the third figure.

10. In an amusement device, a platform, a pair of arms, one end of each arm being pivotally connected to the platform, a figure pivotally supported on the other ends of said arms, a second figure pivotally supported on the platform in advance of and in alignment with said movable figure, means for throwing the first mentioned figure against the second figure, means for locking the first figure against movement, a target disk carried by said locking means, and a third figure having a movable member connected to one of the first two figures, whereby the operation of the target disk will operate the first two figures and the movable member of the third figure.

WALTER ROYAL LOCKHART.
